(57) **CLAIM**

The ornamental design for an accessory for nasal aspirator, as shown and described.

DESCRIPTION

FIG. 1 is a front perspective view of an accessory nasal aspirator showing my new design;

(Continued)

FIG. 2 is a rear perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof; and,
FIG. 8 is a bottom plan view thereof.
The broken lines in the figures depict portions of the
accessory for nasal aspirator, that form no part of the
claimed design.

1 Claim, 8 Drawing Sheets

FIG. 1

FIG. 2

FIG.3

FIG.4

FIG. 5

FIG. 6
